UNITED STATES PATENT OFFICE.

BURTON H. GEDGE, OF ANDERSON, INDIANA.

ROOFING MEMBER.

1,119,946.

Specification of Letters Patent.

Patented Dec. 8, 1914.

Application filed February 27, 1913. Serial No. 750,975.

To all whom it may concern:

Be it known that I, BURTON H. GEDGE, a citizen of the United States, residing at Anderson, in the county of Madison and State of Indiana, have invented a new and useful Roofing Member, of which the following is a specification.

The object of my invention is to produce a sheet metal roofing member which may be easily and cheaply constructed and of such character as to avoid the objections heretofore resulting from the use of present sheet metal roofing members because of capillary attraction.

15. The accompanying drawings illustrate my invention.

Figure 1 is a perspective view of a small section of the roof covered by a fragment of two adjacent and mating roofing members of my improved type; and Fig. 2 a fragmentary perspective of a modified form.

In the drawings, 10 indicates the main body of a sheet of metal such as is commonly used in the production of roofing members. At one edge sheet 10 is provided with an upturned lip 11 which preferably lies at a slightly obtuse angle to the main body of the sheet. At the opposite edge sheet 10 is provided with a lip 12 the vertical height of which is less than the vertical height of lip 11. There may be considerable range in the variation of height of these two lips, but in practice the difference will probably be from $\frac{1}{8}$ to $\frac{1}{2}$ of an inch. Flanking lip 12 is a substantially horizontal lip 13 which may be of any desired width and this lip is in turn flanked by a comparatively short lip 14 which may lie substantially at right angles to the plane of lip 13. The lip 13 is not quite parallel with the main body 10 but is upwardly inclined by an amount sufficient to substantially compensate the difference in height between lips 11 and 12.

45. In applying my improved member to a roof, I provide, as is usual in such cases, a wooden roof 15 and this roof is longitudinally stripped, at appropriate intervals, with wood strips 16, the height of which is substantially equal to the vertical height of lips 12 beneath the lips 13, and the widths of which are a little less than the width of lip 13, the strips 16 being spaced apart a distance equal, or substantially equal, to the distance 55 between the upper ends of the lips 11 and 12 of a roofing plate. When the plates are as-

sembled, as clearly indicated in the drawings, lips 13 and 14 overlie the upper edge of lip 11 of the adjacent sheet, whereupon nails 17, or other suitable fastening members, are driven through lips 13 into the ribs 16, thus not only holding the sheets in place, but also springing lips 13 slightly downwardly so as to tighten said lips down upon the upper edge of the overlaid lip 11. 60 This gives a substantially sharp line of contact between adjacent roofing members and also provides a wedge-shaped space 18 immediately beneath the lip 13, said wedge-shaped space being too great to cause any 70 water, entrapped between lips 11 and 14, to creep into and fill the space. As a consequence, any water which may splash from the main body of the sheet upwardly into the space between the lips 11 and 14, will be 75 prevented from passing beyond the line of contact between the upper edge of lip 11 and the lip 13.

The construction shown in Fig. 2 is very similar to that shown in Fig. 1 except that 80 the upstanding lip 11' (which corresponds to the lip 11 in the other form) is flanked by a trough 20 which is of sufficient depth to avoid becoming filled by capillary action and the outer lip of which is of sufficient 85 height to engage the overlying lip 13 of an adjacent sheet. By this arrangement the trough 20 will stiffen the lip 13 and prevent too great a depression thereof when the fastening members 17 are driven into place, 90 thus avoiding any tendency, which might possibly exist in the other form, of an upward buckling of the main body of the sheet if the fastening members 17 are driven 95 too tightly in place.

I claim as my invention:

1. A sheet roofing member comprising a main sheet having an upstanding lip formed along one edge, and an upstanding lip formed along the opposite edge and of less height than the first mentioned lip, said second lip being flanked by a substantially horizontal lip which in turn is flanked by a down-turned lip.

2. The combination with a sheet roofing member comprising a main sheet having an upstanding lip formed along one edge, and an upstanding lip formed along the opposite edge and of less height than the first mentioned lip, said second lip being flanked by a substantially horizontal lip which in turn is flanked by a down-turned lip, of a sup-

- porting structure provided with upstanding ribs having a height less than the taller lip of a roofing sheet and a width less than the horizontal width of the horizontal lip 5 of the roofing sheet, and fastening members driven through the horizontal lip into the sub-structure so as to spring the horizontal lip downwardly upon the upper edge of the taller upstanding lip.
- 10 3. The combination with a sheet roofing member comprising a main sheet having an upstanding lip formed along one edge, and an upstanding lip formed along the opposite edge, said second lip being flanked by a sub- 15 substantially horizontal lip which in turn is flanked by a down-turned lip, of a supporting structure provided with upstanding ribs having a height less than an adjacent lip of a roofing sheet and a width less than the 20 horizontal width of the horizontal lip of the roofing sheet, and fastening members driven through the horizontal lip into the sub-structure so as to spring the horizontal lip downwardly upon the upper edge of the 25 adjacent upstanding lip.
4. A sheet roofing member comprising a main sheet having an upstanding lip formed along one edge flanked by an upwardly presented trough, and an upstanding lip formed 30 along the opposite edge of less height than the first mentioned lip, said second lip being flanked by a substantially horizontal lip which in turn is flanked by a down-turned lip.
- 35 5. The combination with a sheet roofing member comprising a main sheet having an upstanding lip formed along one edge and flanked by an upwardly presented trough,
- and an upstanding lip formed along the opposite edge and of less height than the first 40 mentioned lip, said second lip being flanked by a substantially horizontal lip which in turn is flanked by a down-turned lip, of a supporting structure provided with upstanding ribs having a height sufficient to 45 receive and support the trough-like portion of the roofing sheet and a width less than the horizontal width of the horizontal lip of the roofing sheet, and fastening members driven through the horizontal lip into the 50 sub-structure alongside the trough portion.
6. The combination with a sheet roofing member comprising a main sheet having an upstanding lip formed along one edge and flanked by an upwardly presented trough, 55 and an upstanding lip formed along the opposite edge, said second lip being flanked by a substantially horizontal lip which in turn is flanked by a down-turned lip, of a supporting structure provided with upstanding ribs having a height sufficient to receive and support the trough-like portion of the roofing sheet and a width less than the horizontal width of the horizontal lip of the roofing sheet, and fastening members driven through the horizontal lip into the sub-structure alongside the trough portion. 60
- In witness whereof, I, have hereunto set my hand at Indianapolis, Indiana, this 11th day of February, A. D. one thousand nine hundred and thirteen. 70

BURTON H. GEDGE.
